UNITED STATES PATENT OFFICE.

FRANK D. HABERMAN, OF DES MOINES RIVER TOWNSHIP, MINNESOTA.

STUB-SHOE ATTACHMENT FOR RUNNERS OF CORN PLANTERS OR THE LIKE.

Application filed October 21, 1926. Serial No. 143,234.

This invention relates to a stub shoe attachment for the runner of a corn planter or the like, and it is an object of the invention to provide an attachment of this kind

5 which serves to deflect stones or the like which may be in the path of the runner or shoe proper and which also operates to open up the ground in advance of the runner or shoe proper and more particularly to cut 10 through sod or the like to produce a clearance for the runner proper.

The invention consists in the details of construction and in the combination and arrangement of the several parts of my improved stub shoe attachment whereby certain important advantages are attained and the device rendered simpler, less expensive and otherwise more convenient and advantageous for use, as will be hereinafter more 20 fully set forth.

The novel features of my invention will hereinafter be definitely claimed.

In order that my invention may be the better understood, I will now proceed to 25 describe the same with reference to the accompanying drawing, wherein:

Figure 1 is a view in side elevation illustrating a stub shoe constructed in accordance with an embodiment of my invention in 30 applied position;

Figure 2 is a view in top plan of the structure as illustrated in Figure 1.

As disclosed in the accompanying drawing, R denotes a runner or shoe of a conventional type employed in connection with 35 a corn planter or the like.

Pivottally connected, as at 1, with the forward end portion of the runner or shoe R is the upper portion of a stub shoe S. This 40 shoe S comprises an elongated plate or blade disposed in a vertical direction and has its lower forward marginal portion disposed on an outward curvature whereby is provided an entering point 2. The forward 45 marginal portion of the shoe S immediately adjacent the point 2 and extending upwardly a predetermined distance is provided with a knife edge 3 which serves to cut through sod or the like to assure an effective clearance 50 for the runner or shoe R.

Pivottally connected with the shoe S at substantially the central part thereof is an end portion of a rearwardly directed rod 4 which is slidably disposed through a laterally directed lug 5 carried by the upper rear 55 portion of the runner or shoe R, the out-

ward or forward movement of such rod being limited by the pins 6 selectively disposed through one of the openings 7 for contact with the lug 5.

60

Slidably mounted on the forward portion of the rod 4 is a sleeve or collar 8 held in desired position upon the rod by a set screw 9 or the like. Interposed between this sleeve or collar 8 and the lug 5 is an expandable member 10 herein disclosed as a coil spring encircling the rod 4 and which serves to normally maintain the shoe S at the limit of its forward movement.

65

By varying the position of the sleeve or collar 8 the tension of the expandable member or spring 10 may be regulated or controlled as the requirements of practice may prefer.

70

In practice, the shoe S serves to deflect 75 from the path of the runner or shoe R stones or the like which might otherwise interfere therewith and to provide requisite clearance for the runner or shoe R. In the event, however, the shoe S should come in contact 80 with abnormal resistance offered by a stone, root or the like, the shoe S will swing upwardly against the tension of the member or spring 10 to clear such obstruction without injury to the shoe S or the associated 85 part. When the shoe S is free of such obstruction the member or spring 10 automatically returns the shoe to its normal working position.

80

From the foregoing description it is 90 thought to be obvious that stub shoe attachment constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as 95 limiting myself to the precise arrangement and formation of the several parts herein shown in carrying out my invention in practice except as hereinafter claimed.

100

I claim:

105

1. In combination with the runner of a planter, a vertically disposed shoe pivotally engaged with the forward portion of the planter, a rod pivotally engaged with the shoe and slidably engaged with the rear portion of the runner, and yieldable means co-acting with the shoe and rod for normally 110

maintaining the shoe in its working position.

2. In combination with the runner of a planter provided with a laterally disposed projection at its rear portion, a vertically disposed shoe pivotally connected with the forward portion of the runner, a rod pivotally connected with the central portion of the shoe and slidably disposed through the lateral projection of the runner, means car-

ried by the rod and contacting with the projection to limit the forward swinging movement of the shoe, and an expansible spring coacting with the lateral projection of the runner and the forward portion of the rod for normally maintaining the shoe at the limit of its forward movement.

In testimony whereof I hereunto affix my signature.

FRANK D. HABERMAN.
